H. FRANK

BURGLAR PROTECTION

Filed July 17, 1925

INVENTOR.
Harry Frank
BY *Geo. H. Giffen*
ATTORNEYS.

UNITED STATES PATENT OFFICE.

HARRY FRANK, OF BROOKLYN, NEW YORK.

BURGLAR PROTECTION.

Application filed July 17, 1925. Serial No. 44,175.

To all whom it may concern:

Be it known that I, HARRY FRANK, a citizen of Russia, residing at Brooklyn, county of Kings, and State of New York, have invented a certain new and useful Burglar Protection, of which the following is a specification.

This invention relates to the protection of money, valuables, etc., against burglary or hold up. The object of the invention is to provide simple, inexpensive and highly efficient means for foiling attempts to burglarize or hold-up banks, jewelry establishments, express offices, and other places where money or valuables are kept.

Speaking generally, the invention consists in the utilization of a simple and novel tower of bullet proof construction mounted in a position wherein it will be inaccessible to bandits or robbers, but in such manner that it will overlook from a commanding position the normal public portion of a bank, store, show room or the like. The tower comprises a suitable enclosure of bullet proof material supported at a normally inaccessible height above the floor on a suitable framework or legs. It is of sufficient size to comfortably house an armed guard and is provided in its walls with openings or loop holes which command the view of practically the entire floor and through which the guard can keep constant watch for lawlessness and can direct an attack against law breakers.

An important feature of the invention resides in the fact that the guard enclosing portion of the tower is situated at an appreciable distance above the floor and is normally inaccessible by persons on the floor. A ladder or other suitable means may be provided to permit the guard to enter the enclosure, but this ladder is removable and is removed after the guard is positioned in the tower thereby effectually precluding bandits from reaching the guard and engaging in personal conflict with him.

The enclosure is provided with a suitable door adapted to be locked from the inside and the back of such enclosure whereat the door is positioned is imperforate, so that the guard cannot be surprised from the rear. The enclosure is roofed over and within the enclosure are suitable alarm devices including telephone connection and audible alarm controlling means, so that the guard is not only able to fire upon lawless persons, but

he is also enabled to telephone for assistance and to operate a local alarm for the purpose of giving a signal in the immediate vicinity of the establishment in which a hold up may be taking place.

A paramount feature of the invention resides in the fact that the tower is so positioned that it cannot be entered by anyone except the guard whose duties require his presence constantly at this point. In other words, it is not possible, in accordance with the present invention, for example, for a bank teller, in the event of a hold up to seek refuge in the tower. There is absolutely no connection between the tower and the tellers' cages and after the guard is in position in the tower, all means whereby access may be had to the tower is removed. This fact eliminates collusion on the part of employees and robbers.

It has heretofore been suggested to provide bullet proof enclosures into which a bank teller could flee in the event of hold up and from which he could fire upon assailants.

It is found in practice, however, that when the hold up occurs, the person held up is invariably so intimidated by the bandit, that he is afraid to make any move to reach the safety compartment or to fire upon the bandit even though he is successful in reaching the tower. The devices such as heretofore have been suggested, are wholly inadequate from the standpoint of protection either to the individual or to the valuables entrusted in his care. I therefore make no claim to safety compartments connected with tellers' cages, but direct the invention in contradistinction to towers removed from the tellers' cages and in which a guard is seated for the undivided duty of being constantly on watch for attempt at burglary or other lawlessness.

In accordance with this invention, the guard occupying the tower can watch the activities of customers or clients and upon discerning any irregularities is in a position to command the situation, to summon help and to fire upon law breakers if the circumstances warrant it.

Features of the invention, other than those adverted to, will be apparent from the hereinafter detailed description and claims, when read in conjunction with the accompanying drawings.

The accompanying drawings illustrate one

practical embodiment of the invention, but the construction therein shown is to be understood as illustrative, only, and not as defining the limits of the invention.

5. Figure 1 is a perspective view showing a portion of a bank house in which the present invention is installed; and,

10. Figure 2 is a section perspective through the tower taken in the plane of the line 2—2 of Figure 1.

15. In Figure 1 of the drawings, I have shown the present invention, for the purpose of illustration, as installed within a bank, wherein 1 designates the space normally used by the public, and 2 the several tellers' cages about the margins of the space. 3 is the wall at the blind end of the enclosure, the entrance door or doors being at the side of the room opposite or contiguous to the 20 wall 3.

25. The tower of the present invention is shown as embodying an enclosure 4 mounted on suitable supports 5 raised upon the floor of the space 1 and extending upwardly for an appreciable height, preferably to a point beyond the reach of persons on the floor. The supports 5 may be of any suitable number or shape and serve to support the enclosure 4 at a sufficiently high elevation to 30 make the occupant of the enclosure perfectly safe from hand to hand attack and to permit him to command a full view of all persons in the public space of the bank. This provides an open space beneath the tower so as not to interfere with the movement of the patrons of the bank and others. The 35 enclosure 4 is preferably constructed of bullet proof steel, and is closed at three sides, at its top, and at its bottom. Its back is partially closed by a wall 6 and a sliding door 7. This door is preferably provided with means for locking it from the inner side so that it cannot be opened from 40 without.

45. In Figure 2, the door is shown in its normally closed position in full lines and in its opened position in dotted lines. The front and side walls of the enclosure are provided with apertures or loop holes 8 at a 50 convenient height to permit a guard positioned within the enclosure to observe the activities in the space 1 and to fire through these loop holes in the event of necessity. The guard may enter the enclosure by means 55 of a ladder 9, shown in Figure 1 in dotted lines, but, in practice, this ladder is preferably a collapsible ladder, so that after the 60 guard is in the enclosure, the ladder can be drawn up and housed in the enclosure with him, so as to preclude anyone else from gaining access to the enclosure.

65. As shown in Figure 2, the enclosure preferably has housed therein a telephone connection 10, as well as push buttons 11 and 12. The push button 11 is shown as included

in a local circuit with an audible alarm 14, while the push button 12 is included in a circuit which controls the locking of the doors of a building. Circuits of this latter character are well known in the art and it 70 has not been considered necessary to illustrate all the conventional mechanism normally included therein. By means of these various electrical devices, however, the guard is not only able to communicate with police 75 headquarters or otherwise to secure outside assistance, but he can also cause a ringing of the local alarm 14 and furthermore effect the closing of the doors of the bank by means of the switch 12 if he so desires. 80

It will be apparent from what has been said with reference to this invention that the invention provides simple yet thoroughly efficient means to satisfactorily cope with attempt at burglary or hold up. The invention has been particularly described in conjunction with banks, but I am also aware that it can be used to advantage in a wide variety of other business places; e. g., in jewelry stores, express offices, for fur display 90 salons, and in all other places where valuables are kept.

I wish to make it particularly clear the importance of having the tower inaccessible to occupants of the bank other than the 95 guard who is housed in the tower and thoroughly guarded against personal attack.

The foregoing detailed description sets forth the invention in its preferred practical form and the invention is to be understood as fully commensurate with the appended claim.

Having thus fully described the invention, what I claim as new and desire to secure by Letters Patent is:

105. In a business establishment having a cage or counter at which valuables are dealt in and a space before the counter for patrons, a tower positioned in removed relation with respect to the cage or counter and inaccessible therefrom, said tower embodying a bullet proof guard enclosure mounted on suitable leg supports at a sufficiently high elevation to provide an open space beneath the tower and to command thorough view of the 110 counter and patrons and to be inaccessible without the employment of extraneous means, said enclosure having loop holes through which the guard can see and shoot, means to permit the guard to gain access to 115 the enclosure, which means is normally out of cooperation with the tower, whereby the guard is safe from attack and can exercise full surveillance over the activities of 120 patrons and intruders, and alarm means controllable from within the enclosure.

125. In testimony whereof I have signed the foregoing specification.

HARRY FRANK.
